DESIGN FOR A BLOUSE

Irving Geist, New York, N. Y.

Application December 26, 1941, Serial No. 104,848

Term of patent 3½ years

To all whom it may concern:

Be it known that I, Irving Geist, a citizen of the United States, residing in New York city, in the county of New York and State of New York, have invented a new, original, and ornamental Design for a Blouse, of which the following is a specification, reference being had to the accompanying drawing, forming part thereof.

Fig. 1 is a front view of a blouse showing my new design.

Fig. 2 is a rear view of the blouse shown in Fig. 1.

Fig. 3 is an enlarged fragmentary side view of the blouse shown in Fig. 1, with the collar and reverses turned up to show the shoulder and pocket structure of the blouse.

I claim:

The ornamental design for a blouse, substantially as shown and described.

IRVING GEIST.
